ATTORNEY.

UNITED STATES PATENT OFFICE.

ERIK AUGUST FORSBERG, OF STOCKHOLM, SWEDEN, ASSIGNOR TO THE DE LAVAL SEPARATOR COMPANY, OF NEW YORK, N. Y., A CORPORATION OF NEW JERSEY.

PROCESS AND MEANS FOR PREVENTING ONE OF TWO CENTRIFUGALLY-SEPARATED LIQUIDS FROM CONTAMINATING THE OTHER.

Application filed October 20, 1923. Serial No. 669,655.

To all whom it may concern:

Be it known that I, ERIK AUGUST FORSBERG, a subject of the King of Sweden, residing at Stockholm, Sweden, have invented 5 a new and useful Improvement in Processes and Means for Preventing One of Two Centrifugally-Separated Liquids from Contaminating the Other, of which the following is a full, clear, and exact description, reference 10 being had to the accompanying drawings, which form a part of this specification.

In the centrifugal separation of a liquid from a contaminating liquid of different specific gravity, whether or not they are admixed with solid impurities, it is possible, 15 with the most nearly perfected type of centrifuge, to effect a practically complete separation within the bowl of the liquid that it is desired to recover in a pure condition and to 20 discharge the liquid in that condition from the bowl outlet. Heavy solid impurities will be retained on the inner wall of the bowl until the separating operation is finished, but it is nearly always desirable to provide 25 the bowl with a separate outlet for the continuous discharge of the contaminating liquid, and that is always imperative if the total volume of mixed liquid is large or if the contaminating liquid is present in a 30 considerable proportion. During the discharge of the two liquids from their respective outlets, the difficulty arises that there is a tendency for a small proportion of the contaminating liquid to remix with the other 35 liquid. This tendency will be more readily understood by explaining, in general, the construction of a typical bowl and its receiving pans. It will be assumed, in this explanation, that it is sought to dehydrate 40 transformer oil or switch oil, which are examples of liquids which must be purified to an almost absolute degree and which, therefore, cannot be successfully treated by the 45 centrifugal separation process if there is any appreciable remixing of water with oil during the discharge of the two liquids.

A typical two-outlet centrifugal bowl has its heavier liquid discharge outlet (in the case assumed, the water outlet) near the top 50 of the bowl just below its neck and relatively distant from the axis of rotation. The lighter liquid discharge outlet (in the case assumed, the oil outlet) is located in the neck

of the bowl above the water outlet and relatively near the axis of rotation. There is 55 usually a third, or overflow, outlet at the top of the neck of the bowl. Surrounding, the upper part and neck of the bowl are a corresponding number of covers or receiving pans or receptacles. In the construction assumed, there would therefore be three receptacles: a lower one for the water, a middle one for the oil and an upper one to receive any overflow in case the bowl should become loaded beyond its capacity. The 60 pans, which are stationary, are necessarily provided with central orifices of greater diameter than the parts of the bowl that they respectively surround, leaving an annular space between the bowl and each pan. 70

Assuming that the bowl is functioning efficiently, when the oil discharges from the bowl and streams, across the annular space mentioned, into the oil receptacle, it is practically free from water. A short distance 75 below the oil discharge, water is simultaneously streaming into the water receptacle. It is clear that if even a very small proportion of water in this discharging stream mixes with the discharging stream of oil, the oil will not pass into the oil receptacle in a completely dehydrated condition. This 80 remixing does actually occur. The explanation of the phenomenon is that the water is discharged in finely divided drops or particles which remain suspended in the air and also that the air itself becomes saturated with dissolved moisture. 85

Means have been devised with the object 90 in view of preventing fine drops of water suspended in the air from getting into the oil receptacle, and certain of such means have been fairly effective. It may be questioned, however, whether such means ever prevent the finest water particles from being 95 carried by the air whirls into the oil stream; and it is certain that such means do not prevent moisture dissolved in the air from rising to the discharging oil stream and there being caught by the discharging oil, especially as the latter is partly in the form of a very fine spray. 100

The present invention is designed to effectually prevent any water, either in the form of drops or particles or discharged moisture, from being carried by the oil 105

into the discharge spouts of the stationary receptacle that receives the oil discharged from the bowl, and the object is accomplished: first, by deterring the passage of 5 water in any form from the water discharge of the bowl to the oil discharge thereof; secondly, by preventing the precipitation in the oil of water or moisture that is in the immediate vicinity of the stream or spray 10 of oil that is being discharged from the bowl; and thirdly, removing from the oil, as it is sprayed from the oil discharge into the receptacle, any suspended, adhering, or precipitated water or moisture that is carried 15 by the oil spray toward or into the receiving space of the receptacle: thereby preventing any water from being carried with the oil out of the receptacle into the ultimate receiver for the oil. The invention is also 20 applicable to the process of separating water from liquids other than oil and may be found applicable to the separation of other liquids of different specific gravities.

In the drawings:

25 Fig. 1 is a vertical sectional view illustrating a centrifugal bowl, its housing, the receiving pans and a preferred embodiment of my improved means for accomplishing the above specified result.

30 Fig. 2 is a similar view showing a modification.

The centrifugal bowl *a* is supported and rotated in any known way and is provided with the usual surrounding housing *b*. At 35 any point or arc of the circumference *c* is the discharge for water. The oil discharges at any point or arc of the circumference *d*. The overflow discharge, if such be provided, is indicated at *e*. Four stationary pans and covers are provided, each one of which except the lowest forms the top or cover of one receptacle and each one of 40 which except the highest forms the bottom of one receptacle; thereby forming three receptacles, one, *f*, for water, another, *g*, for oil, and a third, *h*, for overflow. The receptacles are provided respectively with the discharge spouts *i*, *j* and *k*. The above described construction and arrangement are 45 old and customary.

50 Referring to Fig. 1, a tube *m* extends into the discharge spout *j*, its open end terminating approximately above the central opening of the pan beneath the oil discharge (lighter liquid outlet) of the bowl. Through this tube heated air is blown. A convenient means of creating a draft of heated air comprises a fan *n* and an electric heater *o* through which atmospheric air is successively conveyed into the tube *m*. The current of air blown out of the tube *m* spreads itself within the central part of the oil receptacle. Inasmuch as heated air has a greater capacity for absorbing moisture than 55 cold air, the saturating degree of moisture

of the air in the oil receptacle is reduced and thus any small drops of water that are suspended in the air are vaporized and dissolved by the air. Any water that may adhere to the oil is vaporized and dissolved by 70 the air. The heated air has thus a pronounced drying or dehydrating effect on the oil. The action of the heated air is very intensive by reason of the fact that both the water and oil are discharged from the bowl 75 in a very finely divided form. The heated air outflows down toward the water discharge from the bowl or up past the overflow discharge or in both directions; any flow of heated air toward the water discharge tends 80 to prevent the passage of water in an opposite direction and therefore deterring an initial mixing of water with the oil spray.

A permissible modification is shown in Fig. 2, in which a tube *p* extends into the oil receptacle and is formed therein into a coil. Through this tube and coil circulates a heating medium, such as hot water or steam. It will be understood that the rotation of the bowl has an effect upon the surrounding air similar to that of a fan or rotating ventilator, thereby tending to displace the air from the housing and draw in air through the several spouts and receptacles and down around the bowl neck into the 95 space within the housing. Air inflowing through the spout *j* directly contacts with the heated tube *p* and is heated by the time it approaches the stream of oil being discharged from the bowl and therefore acts 100 in a similar manner to the hot air blown out of the tube *m* in Fig. 1.

The characteristic feature of the invention is the production of a current of air, at a temperature substantially higher than that 105 of the surrounding air, into the vessel that collects the separated liquid, such as oil, which it is desired to recover in a pure condition, so as to prevent the precipitation of any unprecipitated contaminating liquid, 110 such as water, that, escaping from its separate discharge, has remixed with the oil, and also to absorb any contaminating liquid that may have been precipitated.

115 It is clear that the invention is not limited to the specific means shown and described, and it is also clear that the process is not dependent, for its successful execution, upon the employment of any particular means for producing the described current of heated 120 air.

I am aware that it is not broadly novel, in the process of separating mineral oil from wax, to heat the receiving vessel for the wax, as by a steam jacket, so as to directly heat 125 the wax and thereby increase its fluidity and facilitate its outflow through the discharge spout. In this process, however, the exclusion of minute quantities of oil from the discharging wax is of little or no import- 130

tance and the steam jacket is applied to the receptacle for receiving the liquid (wax) discharged from the heavier liquid outlet from the bowl.

5 Having now fully described my invention, what I claim and desire to protect by Letters Patent is:

1. In the centrifugal separation of water from a liquid of different specific gravity, 10 the process of preventing, after such separation, the contamination of such liquid discharging from the separating bowl by the discharging water, which comprises creating a flow of heated air in the neighborhood 15 of the locus of discharge of said liquid from the bowl, thereby tending to prevent the precipitation of water in the liquid and to effect the dehydration of any part of the liquid to which water has adhered.
2. In the centrifugal separation of water from a liquid of different specific gravity, 20 the process of preventing, after such separation, the contamination of such liquid discharging from the separating bowl by the 25 discharging water, which comprises creating a flow of heated air toward and past the locus of discharge of such liquid from the bowl, thereby tending to prevent the precipitation of water in the liquid and to 30 dry any liquid in which water has been precipitated and also by reason of the direction of flow of the heated air, deterring the passage into the stream of liquid discharging from the bowl of water that has 35 discharged therefrom.
3. In the centrifugal separation of water from a liquid of different specific gravity, 40 the process of preventing, after such separation, the contamination of such liquid discharging from the centrifugal bowl by the discharging water, which comprises creating a draft of air toward the locus of discharge of said liquid from the bowl and heating said air before it reaches said locus.
4. In a centrifugal apparatus, the combination of a rotary separating bowl provided with a plurality of discharges for liquids of different specific gravities, a re-

ceptacle surrounding the bowl and positioned to receive the liquid discharged from 50 the bowl which it is desired to recover in a pure condition, means creating a flow of air through said receptacle toward the corresponding bowl discharge, and means to heat said air.

5. In a centrifugal apparatus, the combination of a rotary separating bowl provided with an upper outlet for the discharge of the lighter separated liquid and a lower outlet for the discharge of the 60 heavier separated liquid, receptacles, one over the other, positioned to receive the liquids delivered from the respective bowl discharges, and means to substantially raise 65 the temperature of the air surrounding the stream of liquid being delivered from the upper bowl outlet into the upper receptacle.

6. In a centrifugal apparatus, the combination of a rotary separating bowl provided with an upper outlet for the discharge 70 of the lighter separated liquid and a lower outlet for the discharge of the heavier separated liquid, receptacles, one over the other, positioned to receive the liquids delivered from the respective bowl discharges, means 75 creating a flow of air through the upper receptacle toward the corresponding bowl outlet, and means to heat said air.

7. In a centrifugal apparatus, the combination of a rotary separating bowl provided with a plurality of discharges for liquids of different specific gravities, a receptacle surrounding the bowl and positioned to receive the liquid delivered from one of said discharges, a pipe entering said 85 receptacle, said pipe opening in the neighborhood of the stream of liquid discharging from the bowl into said receptacle, means to blow air through said pipe and out said opening, and means to heat the air blown 90 through said pipe.

In testimony of which invention, I have hereunto set my hand, at Stockholm, on this the 4th day of October, 1923.

ERIK AUGUST FORSBERG.
